(57) **CLAIM**

We claim an ornamental design for a hand lever, as shown and described.

DESCRIPTION

The subject matter disclosed and claimed herein is related to the subject matter disclosed and claimed in the following U.S. patent applications, each of which was filed on Oct. 27, 2003: U.S. patent application Ser. No. 29/192,617; U.S. patent application Ser. No. 29/192,577; U.S. patent application Ser. No. 29/192,592; U.S. patent application Ser. No. 29/192,593; U.S. patent application Ser. No. 29/192,576; U.S. patent application Ser. No. 29/192,579; and U.S. patent application Ser. No. 29/192,585.

FIG. 1 is a top plan view of a hand lever showing our new design;

FIG. 2 is a bottom plan view thereof;

FIG. 3 is a front elevational view thereof;

FIG. 4 is a rear elevational view thereof; and

FIG. 5 is a side elevational view thereof; and,

FIG. 6 is an opposite side elevational view thereof.

The dashed lines shown in the views are for illustrative or disclosure purposes only, and form no part of the claimed design.
